REPRODUCTION MACHINE HAVING DUPLEX JOB RECOVERY CAPABILITIES

BACKGROUND OF THE INVENTION

This invention relates to a reproduction machine capable of making duplex copies from a set of original documents. More particularly, it involves a control system for automatically adjusting the reproduction process of such a machine in the event of a fault condition so that the selected number of copies are ultimately produced even though some copies may have been lost due to the fault occurring during the middle of a copy run.

As processing speeds of modern day reproduction machines become increasingly faster, and machine accessories such as sorters, collators, binders, document handlers, etc. become more prevalent, the problem of recouping or saving a specific job in the event of a machine malfunction or fault condition, such as, for example, a paper jam, becomes almost impossible. It will be understood that protection against fault conditions like paper jams is provided through safety controls designed to stop the machine, as well as any accessories used therewith. The jammed papers, which are usually damaged or mutilated, are then removed and the machine restarted. However, loss of these partially processed copies upsets the copy run, since, if the system is merely restarted, the number of copies made will not equal the number of copies selected. This, of course, is due to the loss of some copies in clearing the machine.

Thus, to ultimately produce the number of copies selected, some provision for making up the copies lost as a result of clearing the jam must be made. Unfortunately, this is an extremely task in modern high speed reproduction machines, particularly those employing accessories such as a document handler, since it is difficult to determine exactly how many copies are actually lost and to identify those copies lost with the correct original. Rather than go through a complicated evaluation, many users may tend to simply start the entire copy run anew, discarding even those copies which have been successfully completed. This, of course, can be quite wasteful and expensive, particularly where the job is large and almost completed at the time of the jam.

As described in U.S. Pat. No. 3,944,794 to Reehil et al, the Xerox 9200 copier/duplicator system incorporates a jam recovery technique that has proven to be extremely satisfactory. However, this machine does not include provision for automatically making two sided or duplexed copies. Instead, it merely provides the capability of producing one sided or simplex copies automatically. It is realized that some of the more recent commercially available machines provide the capability of automatically producing duplex copies. However, due to the extreme complexity of such machines, they have not included provision for automatically remaking lost copies in the event of fault conditions.

OBJECTS AND SUMMARY OF THE INVENTION

Therefore, it is the primary object of this invention to provide a method of controlling a reproduction machine to produce duplex copies from a set of original documents and for automatically adjusting the reproduction process in the event of a fault condition so that the selected number of copies are ultimately produced even though some copies have been lost due to the fault.

Another object of this invention is to provide a control system for a reproduction machine with automatically divides the copy run into a plurality of sets of lesser quantity if the selected quantity exceeds the capacity of the machine for the various accessory features selected.

These and other objects of this invention are accomplished by storing the quantity of exposures and delivered copies for each original necessary for successfully completing the selected copy run. A running count of the exposures made from each original is made, as is the number of successfully delivered copies thereof. Means are provided for signalling whether side 1 or side 2 copies are being delivered. In the event of a side 2 delivery fault, the number of side 2 copies successfully delivered is utilized to reset the exposures made and copies delivered counters for the side 1 and side 2 recovery originals which are represented to the machine for remaking lost copies due to the fault.

In a preferred embodiment, the side 1 original is presented to the machine for forming finished copies thereof, with the side 1 copies being delivered to a temporary receptacle. The actual number of exposures made for each original is counted, as is the number of copies actually delivered. The side 2 original is presented to the machine only if there is both exposure and delivery coincidence for the side 1 copies. If so, duplex copies are formed by forming finished copies of the side 2 original on the opposite side of the side 1 copies which are fed from the temporary receptacle. In order to optimize the machine speed, the next side 1 original may be placed on the platen and exposed as soon as there is side 2 exposure coincidence. However, the number of duplex copies subsequently delivered to an output receptacle is also detected and compared with the stored quantity of copies to be delivered for necessary completion. The above procedure is repeated in the event of a fault condition until side 1 and side 2 exposure and delivery coincidences are both met thereby remaking any lost copies due to a fault condition.

The reproduction machine may contain a plurality of accessory features each with a given capacity for processing copies at one time. Their respective capacities are stored and later compared with the number of copies selected by the operator. The copy run is divided into a plurality of sets of lesser quantity if the quantity selected exceeds the capacity of the machine for the features selected.

BRIEF DESCRIPTION OF THE DRAWINGS

Other objects and advantages will be apparent from the ensuing description and drawings in which:

FIG. 1 is a schematic representation of an exemplary reproduction apparatus incorporating the control system of the present invention;

FIG. 2 is a vertical sectional view of the apparatus shown in FIG. 1 along the image plane;

FIG. 3 is a top plane view of the apparatus shown in FIG. 1;

FIG. 4 is an isometric view showing the drive train for the apparatus shown in FIG. 1;

FIG. 5 is an enlarged view showing details of the photoreceptor edge fadeout mechanism for the apparatus shown in FIG. 1;

FIG. 6 is an enlarged view showing details of the developing mechanism for the apparatus shown in FIG. 1;

FIG. 7 is an enlarged view showing details of the developing mechanism drive;

FIG. 28 is a block diagram of the main panel interface module;

FIG. 29 is a block diagram of the input matrix module;

FIG. 30 is a block diagram of a typical remote;

FIG. 31 is a block diagram of the sorter remote;

FIG. 32 is a view of the control console for inputting copy run instructions to the apparatus shown in FIG. 1;

FIG. 33 is a flow chart illustrating a typical machine state;

FIG. 34 is a flow chart of the machine state routine;

FIG. 35 is a view showing the event table layout;

FIG. 36 is a chart illustrating the relative timing sequences of the clock interrupt pulses;

FIG. 37 is a flow chart of the pitch interrupt routine;

FIG. 38 is a flow chart of the machine clock interrupt routine;

FIGS. 39a and 39b comprise a flow chart of the real time interrupt routines;

FIGS. 40a, 40b, 40c are a timing chart of the principal operating components of the host machine in an exemplary copy run; and

FIGS. 41-45 are flow charts illustrating the method of operating the machine to provide duplex copies and for automatically remaking lost copies in the event of a fault condition.

DETAILED DESCRIPTION OF THE PREFERRED EMBODIMENT OF THE INVENTION

Referring particularly to FIGS. 1-3 of the drawings, there is shown, in schematic outline, an electrostatic reproduction system or host machine, identified by numeral 10, incorporating the control arrangement of the present invention. To facilitate description, the reproduction system 10 is divided into a main electrostatic xerographic processor 12, sorter 14, document handler 16, and controller 18. Other processor, sorter and/or document handler types and constructions, and different combinations thereof may instead be envisioned.

PROCESSOR

Processor 12 utilizes a photoreceptor in the form of an endless photoconductive belt 20 supported in generally triangular configuration by rolls 21, 22, 23. Belt supporting rolls 21, 22, 23 are in turn rotatably journaled on subframe 24.

In the exemplary processor illustrated, belt 20 comprises a photoconductive layer of selenium, which is the light receiving surface and imaging medium, on a conductive substrate. Other photoreceptor types and forms, such as comprising organic materials or of multi-layers or a drum may instead be envisioned. Still other forms may comprise scroll type arrangements wherein webs of photoconductive material may be played in and out of the interior of supporting cylinders.

Suitable biasing means (not shown) are provided on subframe 24 to tension the photoreceptor belt 20 and insure movement of belt 20 along a prescribed operating path. Belt tracking switch 25 (shown in FIG. 2) monitors movement of belt 20 from side to side. Belt 20 is supported so as to provide a trio of substantially flat belt runs opposite exposure, developing, and cleaning stations 27, 28, 29 respectfully. To enhance belt flatness at these stations, vacuum platens 30 are provided under belt 20 at each belt run. Conduits 31 communicate vacuum platens 30 with a vacuum pump 32. Photoconductive belt 20 moves in the direction indicated by the solid line arrow, drive thereto being effected through roll 21, which in turn is driven by main drive motor 34, as seen in FIG. 4.

Processor 12 includes a generally rectangular, horizontal transparent platen 35 on which each original 2 to be copied is disposed. A two or four sided illumination assembly, consisting of internal reflectors 36 and flash lamps 37 (shown in FIG. 2) disposed below and along at least two sides of platen 35, is provided for illuminating the original 2 on platen 35. To control temperatures within the illumination space, the assembly is coupled through conduit 33 with a vacuum pump 38 which is adapted to withdraw overly heated air from the space. To retain the original 2 in place on platen 35 and prevent escape of extraneous light from the illumination assembly, a platen cover 35' may be provided.

The light image generated by the illumination system is projected via mirrors 39, 40 and a variable magnification lens assembly 41 onto the photoreceptive belt 20 at

the exposure station 27. Reversible motor 43 is provided to move the main lens and add on lens elements that comprise the lens assembly 41 to different predetermined positions and combinations to provide the preselected image sizes corresponding to push button selectors 818, 819, 820 on operator module 800. (See FIG. 32) Sensors 116, 117, 118 signal the present disposition of lens assembly 41. Exposure of the previously charged belt 20 selectively discharges the photoconductive belt to produce on belt 20 an electrostatic latent image of the original 2. To prepare belt 20 for imaging, belt 20 is uniformly charged to a preselected level by charge corotron 42 upstream of the exposure station 27.

To prevent development of charged but unwanted image areas, erase lamps 44, 45 are provided. Lamp 44, which is referred to herein as the pitch fadeout lamp, is supported in transverse relationship to belt 20, lamp 44 extending across substantially the entire width of belt 20 to erase (i.e. discharge) areas of belt 20 before the first image, between successive images, and after the last image. Lamps 45, which are referred to herein as edge fadeout lamps, serve to erase areas bordering each side of the images. Referring particularly to FIG. 5, edge fadeout lamps 45, which extend transversely to belt 20, are disposed within a housing 46 having a pair of transversely extending openings 47, 47' of differing length adjacent each edge of belt 20. By selectively actuating one or the other of the lamps 45, the width of the area bordering the sides of the image that is erased can be controlled.

Referring to FIGS. 1, 6 and 7, magnetic brush rolls 50 are provided in a developer housing 51 at developing station 28. Housing 51 is pivotally supported adjacent the lower end thereof with interlock switch 52 to sense disposition of housing 51 in operative position adjacent belt 20. The bottom of housing 51 forms a sump within which a supply of developing material is contained. A rotatable auger 54 in the sump area serves to mix the developing material and bring the material into operative relationship with the lowermost of the magnetic brush rolls 50.

As will be understood by those skilled in the art, the electrostatically attractable developing material commonly used in magnetic brush developing apparatus of the type shown comprises a pigmented resinous powder, referred to as toner, and larger granular beads referred to as carrier. To provide the necessary magnetic properties, the carrier is comprised of a magnetizable material such as steel. By virtue of the magnetic fields established by developing rolls 50 and the interrelationship therebetween, a blanket of developing material is formed along the surfaces of developing rolls 50 adjacent the belt 20 and extending from one roll to another. Toner is attracted to the electrostatic latent image from the carrier bristles to produce a visible powder image on the surface of belt 20.

Magnetic brush rolls 50 each comprise a rotatable exterior sleeve 55 with relatively stationary magnet 56 inside. Sleeves 55 are rotated in unison and at substantially the same speed as belt 20 by a developer drive motor 57 through a belt and pulley arrangement 58. A second belt and pulley arrangement 59 drives auger 54.

To regulate development of the latent electrostatic images on belt 20, magnetic brush sleeves 55 are electrically biased. A suitable power supply 60 is provided for this purpose with the amount of bias being regulated by controller 18.

Developing material is returned to the upper portion of developer housing 51 for reuse and is accomplished by utilizing a photocell 62 which monitors the level of developing material in housing 51 and a photocell lamp 62' spaced opposite to the photocell 62 in cooperative relationship therewith. The disclosed machine is also provided with automatic developability control which maintains an optimum proportion of toner-to-carrier material by sensing toner concentration and replenishing toner, as needed. As shown in FIG. 8, the automatic developability control comprises a pair of transparent plates 64 mounted in spaced, parallel arrangement in developer housing 51 such that a portion of the returning developing material passes therebetween. A suitable circuit, not shown, alternately places a charge on the plates 64 to attract toner thereto. Photocell 65 on one side of the plate pair senses the developer material as the material passes therebetween. Lamp 65' on the opposite side of plate pair 64 provides reference illumination. In this arrangement, the returning developing material is alternately attracted and repelled to and from plate 64. The accumulation of toner, i.e. density determines the amount of light transmitted from lamp 65' to photocell 65. Photocell 65 monitors the density of the returning developing material with the signal output therefrom being used by controller 18 to control the amount of fresh or make-up toner to be added to developer housing 51 from toner supply container 67.

To discharge toner from container 67, rotatable dispensing roll 68 is provided in the inlet to developer housing 51. Motor 69 drives roll 68. When fresh toner is required, as determined by the signal from photocell 65, controller 18 actuates motor 69 to turn roll 68 for a timed interval. The rotating roll 68, which is comprised of a relatively porous sponge-like material, carries toner particles thereon into developer housing 51 where it is discharged. Pre-transfer corotron 70 and lamp 71 are provided downstream of magnetic brush rolls 50 to regulate developed image charges before transfer.

A magnetic pick-off roll 72 is rotatably supported opposite belt 20 downstream of pre-transfer lamp 71, roll 72 serving to scavenge leftover carrier from belt 20 preparatory to transfer of the developed image to the copy sheet 3. Motor 73 turns roll 72 in the same direction and at substantially the same speed as belt 20 to prevent scoring or scratching of belt 20. One type of magnetic pick-off roll is shown in U.S. Pat. No. 3,834,804, issued Oct. 10, 1974 to Bhagat et al.

Referring to FIGS. 4, 9 and 12, to transfer developed images from belt 20 to the copy sheets 3, a transfer roll 75 is provided. Transfer roll 75, which forms part of the copy sheet feed path, is rotatably supported within a transfer roll housing opposite belt support roll 21. Housing 76 is pivotally mounted at 76' to permit the transfer roll assembly to be moved into and out of operative relationship with belt 20. A transfer roll cleaning brush 77 is rotatably journaled in transfer roll housing 76 with the brush periphery in contact with transfer roll 90. Transfer roll 75 is driven through contact with belt 20 while cleaning brush 77 is coupled to main drive motor 34. To remove toner, housing 76 is connected through conduit 78 with vacuum pump 81. To facilitate and control transfer of the developed images from belt 20 to the copy sheets 3, a suitable electrical bias is applied to transfer roll 75.

To permit transfer roll 75 to be moved into and out of operative relationship with belt 20, cam 79 is provided in driving contact with transfer roll housing 76. Cam 79

is driven from motor 34 through an electromagnetically operated one revolution clutch 80. Spring means (not shown) serves to maintain housing 76 in driving engagement with cam 79.

To facilitate separation of the copy sheets 3 from belt 20 following transfer of developed images, a detack corotron 82 is provided. Corotron 82 generates a charge designed to neutralize or reduce the charges tending to retain the copy sheet on belt 20. Corotron 82 is supported on transfer roll housing 76 opposite belt 20 and downstream of transfer roll 75.

Referring to FIGS. 1, 2 and 10, to prepare belt 20 for cleaning, residual charges on belt 20 are removed by discharge lamp 84 and preclean corotron 94. A cleaning brush 85, rotatably supported within an evacuated semi-circular shaped brush housing 86 at cleaning station 29, serves to remove residual developer from belt 20. Motor 95 drives brush 85, brush 85 turning in a direction opposite that of belt 20.

Vacuum conduit 87 couples brush housing 86 through a centrifugal type separator 88 with the suction side of vacuum pump 93. A final filter 89 on the outlet of motor 93 traps particles that pass through separator 88. The heavier toner particles separated by separator 88 drop into and are collected in one or more collecting bottles 90. Pressure sensor 91 monitors the condition of final filter 89 while a sensor 92 monitors the level of toner particles in collecting bottles 90.

To obviate the danger of copy sheets remaining on belt 20 and becoming entangled with the belt cleaning mechanism, a deflector 96 is provided upstream of cleaning brush 85. Deflector 96, which is pivotally supported on the brush housing 86, is operated by solenoid 97. In the normal or off position, deflector 96 is spaced from belt 20 (the solid line position shown in the drawings). Energization of solenoid 97 pivots deflector 96 downwardly to bring the deflector leading edge into close proximity to belt 20.

Sensors 98, 99 are provided on each side of deflector 96 for sensing the presence of copy material on belt 20. A signal output from upstream sensor 98 triggers solenoid 97 to pivot deflector 96 into position to intercept the copy sheet on belt 20. The signal from sensor 98 also initiates a system shutdown cycle (mis-strip jam) wherein the various operating components are, within a prescribed interval, brought to a stop. The interval permits any copy sheet present in fuser 150 to be removed, sheet trap solenoid 158 (FIG. 12) having been actuated to prevent the next copy sheet from entering fuser 150 and becoming trapped therein. The signal from sensor 99, indicating failure of deflector 96 to intercept or remove the copy sheet from belt 20, triggers an immediate or hard stop (sheet on selenium jam) of the processor. In such instances the power to drive motor 34 is interrupted to bring belt 20 and the other components driven therefrom to an immediate stop.

Referring particularly to FIGS. 1 and 12, copy sheets 3 comprise precut paper sheets supplied from either main or auxiliary paper trays 100, 102. Each paper tray has a platform or base 103 for supporting in stack-like fashion a quantity of sheets. The tray platforms 103 are supported for vertical up and down movement by motors 105, 106. Side guide pairs 107, in each tray 100, 102 delimit the tray side boundaries, the guide pairs being adjustable toward and away from one another in accommodation of different size sheets. Sensors 108, 109 respond to the position of each side guide pair 107, the output of sensors 108, 109 serving to regulate operation

5 of edge fadeout lamps 45 and fuser cooling valve 171 (FIG. 3). Lower limit switches 110 on each tray prevent overtravel of the tray platform in a downward direction.

A heater 112 is provided below the platform 103 of main tray 100 to warm the tray area and enhance feeding of sheets therefrom. Humidstat 113 and thermostat 114 control operation of heater 112 in response to the temperature/humidity conditions of main tray 100. Fan 115 is provided to circulate air within tray 100.

To advance the sheets 3 from either main or auxiliary tray 100, 102, main and auxiliary sheet feeders 120, 121 are provided. Feeders 120, 121 each include a nudger roll 123 to engage and advance the topmost sheet in the paper tray forward into the nip formed by a feed belt 124 and retard roll 125. Retard rolls 125, which are driven at an extremely low speed by motor 126, cooperate with feed belts 124 to restrict feeding of sheets from trays 100, 102 to one sheet at a time.

Feed belts 124 are driven by main and auxiliary sheet feed motors 127, 128 respectively. Nudger rolls 123 are supported for pivotal movement about the axis of feed belt drive shaft 129 with drive to the nudger rolls taken from drive shaft 129. Stack height sensors 133, 134 are provided for the main and auxiliary trays, the pivoting nudger rolls 123 serving to operate sensors 133, 134 in response to the sheet stack height. Main and auxiliary tray misfeed sensors 135, 136 are provided at the tray outlets.

Main transport 140 extends from main paper tray 100 to a point slightly upstream of the nip formed by photoconductive belt 20 and transfer roll 75. Transport 140 is driven from main motor 34. To register sheets 3 with the images developed on belt 20, sheet register fingers 141 are provided, fingers 141 being arranged to move into and out of the path of the sheets on transport 140 once each revolution (see also FIG. 4). Registration fingers 141 are driven from main motor 34 through electromagnetic clutch 145. A timing or reset switch 146 is set once on each revolution of sheet register fingers 141. Sensor 139 monitors transport 140 for jams. Further amplification of sheet register system may be found in U.S. Pat. No. 3,781,004, issued Dec. 25, 1973 to Buddendeck et al.

Pinch roll pair 142 is interspaced between transport belts that comprise main transport 140 on the downstream side of register fingers 141. Pinch roll pair 142 are driven from main motor 34.

Auxiliary transport 147 extends from auxiliary tray 102 to main transport 140 at a point upstream of sheet register fingers 141. Transport 147 is driven from motor 34.

To maintain the sheets in driving contact with the belts of transports 140, 147, suitable guides or retainers (not shown) may be provided along the belt runs.

The image bearing sheets leaving the nip formed by photoconductive belt 20 and transfer roll 75 are picked off by belts 155 of the leading edge of vacuum transport 149. Belts 155, which are perforated for the admission of vacuum therethrough, ride on forward roller pair 148 and rear roll 153. A pair of internal vacuum plenums 151, 154 are provided, the leading plenum 154 cooperating with belts 155 to pick up the sheets leaving the belt/transfer roll nip. Transport 149 conveys the image bearing sheets to fuser 150. Vacuum conduits 147, 156 communicate plenums 151, 154 with vacuum pumps 152, 152'. A pressure sensor 157 monitors operation of

vacuum pump 152. Sensor 144 monitors transport 149 for jams.

To prevent the sheet on transport 149 from being carried into fuser 150 in the event of a jam or malfunction, a trap solenoid 158 is provided below transport 149. Energization of solenoid 158 raises the armature thereof into contact with the lower face of plenum 154 to intercept and stop the sheet moving therewith.

Referring particularly to FIGS. 4, 10 and 12, fuser 150 comprises a lower heated fusing roll 160 and upper pressure roll 161. Rolls 160, 161 are supported for rotation in fuser housing 162. The core of fusing roll 160 is hollow for receipt of heating rod 163 therewithin.

Housing 162 includes a sump 164 for holding a quantity of liquid release agent, herein termed oil. Dispensing belt 165, moves through sump 164 to pick up the oil, belt 165 being driven by motor 166. A blanket-like wick 167 carries the oil from belt 165 to the surface of fusing roll 160.

Pressure roll 161 is supported within an upper pivotal section 168 of housing 162. This enables pressure roll 161 to be moved into and out of operative contact fusing roll 160. Cam shaft 169 in the lower portion of fuser housing 162 serves to move housing section 168 and pressure roll 161 into operative relationship with fusing roll 160 against a suitable bias (not shown). Cam shaft 169 is coupled to main motor 34 through an electromagnetically operated one revolution clutch 159.

Fuser section 168 is evacuated, conduit 170 coupling housing section 168 with vacuum pump 152. The ends of housing section 168 are separated into vacuum compartments opposite the ends of pressure roll 161 thereunder to cool the roll ends where smaller size copy sheets 3 are being processed. Vacuum valve 171 (FIG. 3) in conduit 172 regulates communication of the vacuum compartments with vacuum pump 153 in response to the size sheets as sensed by side guide sensors 108, 109 in paper trays 100, 102.

Fuser roll 160 is driven from main motor 34. Pressure roll 161 is drivingly coupled to fuser roll 160 for rotation therewith.

Thermostat 174 (FIG. 12) in fuser housing 162 controls operation of heating rod 163 in response to temperature. Sensor 175 protects against fuser over-temperature. To protect against trapping of a sheet in fuser 150 in the event of a jam, sensor 176 is provided.

Following fuser 150, the sheet is carried by post fuser transport 180 to either discharge transport 181 or, where duplex or two sided copies are desired, to return transport 182. Sheet sensor 183 monitors passage of the sheets from fuser 150. Transports 180, 181 are driven from main motor 34. Sensor 181 monitors transport 181 for jams. Suitable retaining means may be provided to retain the sheets on transports 180, 181.

A deflector 184, when extended, directs sheets on transport 180 onto conveyor roll 185 and into chute 186 leading to return transport 182. Solenoid 179, when energized raises deflector 184 into the sheet path. Return transport 182 carries the sheets back to auxiliary tray 102. Sensor 189 monitors transport 182 for jams. The forward stop 187 of tray 102 is supported for oscillating movement. Motor 188 drives stop 187 back and forth tap sheets returned to auxiliary tray 102 into alignment for refeeding.

To invert duplex copy sheets following fusing of the second or duplex image, a displaceable sheet stop 190 is provided adjacent the discharge end of chute 186. Stop 190 is pivotally supported for swinging movement into

and out of chute 186. Solenoid 191 is provided to move stop 190 selectively into or out of chute 186. Pinch roll pairs 192, 193 serve to draw the sheet trapped in chute 186 by stop 190 and carry the sheet forward onto discharge transport 181. Further description of the inverter mechanism may be found in U.S. Pat. No. 3,856,295, issued Dec. 24, 1974, to John H. Looney.

Output tray 195 receives unsorted copies. Transport 196 a portion of which is wrapped around a turn around roll 197, serves to carry the finished copies to tray 195. Sensor 194 monitors transport 196 for jams. To route copies into output tray 195, a deflector 198 is provided. Deflector solenoid 199, when energized, turns deflector 198 to intercept sheets on conveyor 181 and route the sheets onto conveyor 196.

When output tray 195 is not used, the sheets are carried by conveyor 181 to sorter 14.

SORTER

Referring particularly to FIG. 13, sorter 14 comprises upper and lower bin arrays 210, 211. Each bin array 210, 211 consists of series of spaced downwardly inclined trays, forming a series of individual bins 213 for receipt of finished copies 3'. Conveyors 214 along the top of each bin array, cooperate with idler rolls 215 adjacent the inlet to each bin to transport the copies into juxtaposition with the bins. Individual deflectors 216 at each bin cooperate, when depressed, with the adjoining idler roll 215 to turn the copies into the bin associated therewith. An operating solenoid 217 is provided for each deflector.

A driven roll pair 218 is provided at the inlet to sorter 14. A generally vertical conveyor 219 serves to bring copies 3' to the upper bin array 210. Entrance deflector 220 routes the copies selectively to either the upper or lower bin array 210, 211 respectively. Solenoid 221 operates deflector 220.

Motor 222 is provided for each bin array to drive the conveyors 214 and 219 of upper bin array 210 and conveyor 214 of lower bin array 211. Roll pair 218 is drivingly coupled to both motors.

To detect entry of copies 3' in the individual bins 213, a photoelectric type sensor 225, 226 is provided at one end of each bin array 210, 211 respectively. Sensor lamps 225', 226' are disposed adjacent the other end of the bin array. To detect the presence of copies in the bins 213, a second set of photoelectric type sensors 227, 228 is provided for each bin array, on a level with a tray cutout (not shown). Reference lamps 227', 228' are disposed opposite sensors 227, 228.

DOCUMENT HANDLER

Referring particularly to FIGS. 14 and 15, document handler 16 includes a tray 233 into which originals or documents 2 to be copied are placed by the operator following which a cover (not shown) is closed. A movable bail bar or separator 235, driven in an oscillatory path from motor 236 through a solenoid operated one revolution clutch 238, is provided to maintain document separation.

A document feed belt 239 is supported on drive and idler rolls 240, 241 and kicker roll 242 under tray 233, tray 233 being suitably apertured to permit the belt surface to project therewithin. Feedbelt 239 is driven by motor 236 through electromagnetic clutch 244. Guide 245, disposed near the discharge end of feed belt 239, cooperates with belt 239 to form a nip between which the documents pass.

A photoelectric type sensor 246 is disposed adjacent the discharge end of belt 239. Sensor 246 responds on failure of a document to feed within a predetermined interval to actuate solenoid operated clutch 248 which raises kicker roll 242 and increases the surface area of feed belt 239 in contact with the documents. Another sensor 259 located underneath tray 233 provides an output signal when the last document 2 of each set has left the tray 233.

Document guides 250 route the document fed from tray 233 via roll pair 251, 252 to platen 35. Roll 251 is drivingly coupled to motor 236 through electromagnetic clutch 244. Contact of roll 251 with roll 252 turns roll 252.

Roll pair 260, 261 at the entrance to platen 35 advance the document onto platen 35, roll 260 being driven through electromagnetic clutch 262 in the forward direction. Contact of roll 260 with roll 261 turns roll 261 in the document feeding direction. Roll 260 is selectively coupled through gearset 268 with motor 236 through electromagnetic clutch 265 so that on engagement of clutch 265 and disengagement of clutch 262, roll 260 and roll 261 therewith turn in the reverse direction to carry the document back to tray 233 via return chute 276. One way clutches 266, 267 permit free 25 wheeling of the roll drive shafts.

The document leaving roll pair 260, 261 is carried by platen feed belt 270 onto platen 35, belt 270 being comprised of a suitable flexible material having an exterior surface of xerographic white. Belt 270 is carried about 30 drive and idler rolls 271, 272. Roll 271 is drivingly coupled to motor 236 for rotation in either a forward or reverse direction through clutches 262, 265. Engagement of clutch 262 operates through belt and pulley drive 279 to drive belt in the forward direction, engagement of clutch 265 operates through drive 279 to drive belt 270 in the reverse direction.

To locate the document in predetermined position on platen 35, a register 273 is provided at the platen inlet for engagement with the document trailing edge. For 40 this purpose, control of platen belt 270 is such that following transporting of the document onto plate 35 and beyond register 273, belt 270 is reversed to carry the document backwards against register 273.

To remove the document from platen 35 following 45 copying, register 273 is retracted to an inoperative position. Solenoid 274 is provided for moving register 273.

A document deflector 275, is provided to route the document leaving platen 35 into return chute 276. For this purpose, platen belt 270 and pinch roll pair 260, 261 50 are reversed through engagement of clutch 265. Discharge roll pair 278, driven by motor 236, carry the returning document into tray 233.

To monitor movement of the documents in document 55 handler 16 and detect jams and other malfunctions, photoelectric type sensors 246 and 280, 281 and 282 are disposed along the document routes.

To align documents 2 returned to tray 233, a document patter 284 is provided adjacent one end of tray 233. Patter 284 is oscillated by motor 285.

TIMING

To provide the requisite operational synchronization between host machine 10 and controller 18 as will appear, processor or machine clock 202 is provided. Referring particularly to FIG. 1, clock 202 comprises a toothed disc 203 drivingly supported on the output shaft of main drive motor 34. A photoelectric type

signal generator 204 is disposed astride the path followed by the toothed rim of disc 203, generator 204 producing, whenever drive motor 34 is energized, a pulse like signal output at a frequency correlated with the speed of motor 34, and the machine components driven therefrom.

As described, a second machine driven clock, termed a pitch reset clock 138 herein, and comprising timing switch 146 is provided. Switch 146 cooperates with sheet register fingers 141 to generate an output pulse once each revolution of fingers 141. As will appear, the pulse like output of the pitch reset clock is used to reset or resynchronize controller 18 with host machine 10.

Referring to FIG. 15, a document handler clock 286 consisting of apertured disc 287 on the output shaft of document handler drive motor 236 and cooperating photoelectric type signal generator 288 is provided. As in the case of machine clock 202, document handler clock 286 produces an output pulse train from which components of the document handler may be synchronized. A real time clock derived from clock 552 of FIG. 17, is utilized to control internal operations of the controller 18 as is known in the art, as well as the timing of some of the machine components.

CONTROLLER

Referring to FIG. 16, controller 18 includes a Central Processor Unit (CPU) Module 500, Input/Output (I/O) Module 502, and Interface 504. Address, Data and Control Buses 507, 508, 509 respectively operatively couple CPU Module 500 and I/O Module 502. CPU Module 500 I/O Module 502 are disposed within a shield 518 to prevent noise interference.

Interface 504 couples I/O Module 502 with special circuits module 522, input matrix module 524, and main panel interface module 526. Module 504 also couples I/O Module 502 to operating sections of the machine, namely, document handler section 530, input section 532, sorter section 534 and processor sections 536, 538. A spare section 540, which may be used for monitoring operation of the host machine, or which may be later utilized to control other devices, is provided.

Referring to FIGS. 17, 18 CPU module 500 comprises a processor 542 such as an Intel 8080 micro-processor manufactured by Intel Corporation, Santa Clara, Calif., 16K Read Only Memory (herein ROM) and 2K Random Access Memory (herein RAM) sections 545, 546, Memory Ready section 548, power regulator section 550, and onboard clock 552. Bipolar tri-state buffers 510, 511 in Address and Data buses 507, 508 disable the bus on a Direct Memory access (DMA) signal (HOLDA) as will appear. While the capacity of memory sections 545, 546 are indicated throughout as being 16K and 2K respectively, other memory sizes may be readily contemplated.

Referring particularly to FIG. 19, clock 552 comprises a suitable clock oscillator 553 feeding a multi-bit (Qa-Qn) shift register 554. Register 554 includes an internal feedback path from one bit to the serial input of register 554. Output signal waveforms ϕ_1 , ϕ_2 , ϕ_{1-1} and ϕ_{2-1} are produced for use by the system.

Referring to FIG. 20, the memory bytes in ROM section 545 are implemented by address signals (A 0-A 15) from processor 542, selection being effected by 3 to 8 decode chip 560 controlling chip select 1 (CS-1) and a 1 bit selection (A 13) controlling chip select 2 (CS-2). The most significant address bits (A 14, A 15) select the first 16K of the total bytes of the addressing space. The

memory bytes in RAM section 546 are implemented by Address signals (A 0-A 15) through selector circuit 561. Address bit A 10 serves to select the memory bank while the remaining five most significant bits (A 11-A 15) select the last 2K bytes out of the 64K bytes of addressing space. RAM memory section 546 includes a 40 bit output buffer the output of which is tied together with the output from ROM memory section 545 and goes to tri-state buffer 562 to drive Data bus 508. Buffer 562 is enabled when either memory section 545 or 546 is being addressed and either a (MEM READ) or DMA (HOLD A) memory request exists. An enabling signal (MEMEN) is provided from the machine control or service panel (not shown) which is used to permit disabling of buffer 562 during servicing of CPU Module 500. Write control comes from either processor 542 (MEM WRITE) or from DMA (HOLD A) control. Tri-state buffers 563 permit Refresh Control 605 of I/O Module 502 to access MEM READ and MEM WRITE control channels directly on a DMA signal (HOLD A) from processor 542 as will appear.

Referring to FIG. 21, memory ready section 548 provides a READY signal to processor 542. A binary counter 566, which is initialized by a SYNC signal (ϕ_1) to a prewired count as determined by input circuitry 567, counts up at a predetermined rate. At the maximum count, the output at gate 568 comes true stopping the counter 566. If the cycle is a memory request (MEM REQ) and the memory location is on board as determined by the signal (MEM HERE) to tri-state buffer 569, a READY signal is sent to processor 542. Tri-state buffer 570 in MEM REQ line permits Refresh Control 605 of I/O Module 502 to access the MEM REQ channel directly on a DMA signal (HOLD A) from processor 542 as will appear.

Referring to FIG. 22, power regulators 550, 551, 552 provide the various voltage levels, i.e. +5v, +12v, and -5v D.C. required by the module 500. Each of the three on board regulators 550, 551, 552 employ filtered D.C. inputs. Power Not Normal (PNN) detection circuitry 571 is provided to reset processor 542 during the power up time. Panel reset is also provided via PNN. An enabling signal (INHIBIT RESET) allows completion of a write cycle in Non Volatile (N.V.) Memory 610 of I/O Module 502.

Referring to FIGS. 18, 20, 21, and the DMA timing chart (FIG. 18a) data transfer from RAM section 546 to host machine 10 is effected through Direct Memory Access (DMA), as will appear. To initiate DMA, a signal (HOLD) is generated by Refresh Control 605 (FIG. 23a). On acceptance, processor 542 generates a signal HOLD ACKNOWLEDGE (HOLD A) which works through tri-state buffers 510, 511 and through buffers 563 and 570 to release Address bus 507, Data bus 508 and MEM READ, MEM WRITE, and MEM REQ channels (FIGS. 20, 21) to Refresh Control 605 of I/O Module 502.

Referring to FIG. 23, I/O Module 502 interfaces with CPU module 500 through bi-directional Address, Data and Control buses 507, 508, 509. I/O Module 502 appears to CPU module 500 as memory portion. Data transfers between CPU and I/O modules 500, 502, and commands to I/O module 502 except for output refresh are controlled by memory reference instructions executed by CPU module 500. Output refresh which is initiated by one of several uniquely decoded memory reference commands, enables Direct Memory access (DMA) by I/O module 502 to RAM section 546.

I/O module 502 includes Matrix Input select 604 (through which inputs from the host machine 10, are received), Refresh Control 605, Nonvolatile (NV) memory 610, Interrupt Control 612, Watch dog Timer and failure Flag 614 and clock 570.

A Function Decode Section 601 receives and interprets commands from CPU section 500 by decoding information on address bus 507 along with control signals from processor 542 on control bus 509. On command, decode section 601 generates control signals to perform the function indicated. These functions include (a) controlling tri-state buffers 620 to establish the direction of data flow in Data bus 508; (b) strobing data from Data bus 508 into buffer latches 622; (c) controlling multiplexer 624 to put data from Interrupt Control 612, Real Time clock register 621, Matrix Input Select 604 or N.V. memory 610 onto data bus 508; (d) actuating refresh control 605 to initiate a DMA operation; (e) actuating buffers 634 to enable address bits A 0-A 7 to be sent to the host machine 10 for input matrix read operations; (f) commanding operation of Matrix Input Select 604; (g) initiating read or write operation of N.V. memory 610 through Memory Control 638; (h) loading Real Time clock register 621 from data bus 508; and (i) resetting the Watch Dog timer or setting the Fault Failure flag 614. In addition, section 601 includes logic to control and synchronize the READY control line to CPU module 500, the READY line being used to advise module 500 when data placed on the Data bus by I/O module 502 is valid.

Watch dog timer and failure flag 614, which serves to detect certain hardwired and softward malfunctions, comprises a free running counter which under normal circumstances is periodically reset by an output refresh command (REFRESH) from Function Decode Section 601. If an output refresh command is not received within a preset time interval, (i.e. 25m sec) a fault flip flop is set and a signal (FAULT) sent to the host machine 10. The signal (FAULT) also raises the HOLD line to disable CPU Module 500. Clearing of the fault flip flop may be by cycling power or generating a signal (RESET). A selector (not shown) may be provided to disable (DISABLE) the watch dog timer when desired. The fault flip flop may also be set by a command from the CPU Module to indicate that the operating program detected a fault.

Matrix Input select 604 has capacity to read up to 32 groups of eight discrete inputs from host machine 10. Lines A₃ through A₇ of Address bus 507 are routed to host machine 10 via CPU Interface Module 504 to select the desired group of eight inputs. The selected inputs from machine 10 are received via Input Matrix Module 524 (FIG. 28) and are placed by matrix 604 onto data bus 508 and sent to CPU Module 500 via multiplexer 624. Bit selection is effected by lines A₀ through A₂ of Address bus 507.

Output refresh control 605, when initiated, transfers either 16 or 32 sequential words from RAM memory output buffer 546 to host machine 10 at the predetermined clock rate in line 574. Direct Memory access (DMA) is used to facilitate transfer of the data at a relatively high rate. On a Refresh signal from Function Decode Section 601, Refresh Control 605 generates a HOLD signal to processor 542. On acknowledgement (HOLD A) processor 542 enters a hold condition. In this mode, CPU Module 500 releases address and data buses 507, 508 to the high impedance state giving I/O module 502 control thereover. I/O module 502 then

sequentially accesses the 32 memory words from output buffer 546 (REFRESH ADDRESS) and transfers the contents to the host machine 10. CPU Module 500 is dormant during this period.

A control signal (LOAD) in line 607 along with the predetermined clock rate determined by the clock signal (CLOCK) in line 574 is utilized to generate eight 32 bit serial words which are transmitted serially via CPU Interface Module 504 to the host machine remote locations where serial to parallel transformation is performed. Alternatively, the data may be stored in addressable latches and distributed in parallel directly to the required destinations.

N.V. memory 610 comprises a predetermined number of bits of non-volatile memory stored in I/O module 502 under Memory Control 638. N.V. memory 610 appears to CPU module 500 as part of the CPU module memory complement and therefore may be accessed by the standard CPU memory reference instruction set. Referring particularly to FIG. 24, to sustain the contents of N.V. memory 610 should system power be interrupted, one or more rechargeable batteries 635 are provided exterior to I/O module 502. CMOS protective circuitry 636 couples batteries 635 to memory 610 to preserve memory 610 on a failure of the system power. A logic signal (INHIBIT RESET) prevents the CPU Module 500 from being reset during the N.V. memory write cycle interval so that any write operation in progress will be completed before the system is shut down.

For tasks that require frequent servicing, high speed response to external events, or synchronization with the operation of host machine 10, a multiple interrupt system is provided. These comprise machine based interrupts, herein referred to as Pitch Reset interrupt and the Machine interrupt, as well as a third clock driven interrupt, the Real Time interrupt.

Referring particularly to FIGS. 23(a) and 34, the highest priority interrupt signal, Pitch reset signal 640, is generated by the signal output of pitch reset clock 138. The clock signal is fed via optical isolator 645 and digital filter 646 to edge trigger flip flop 647.

The second highest priority interrupt signal, machine clock signal 641, is sent directly from machine clock 202 through isolation transformer 648 to a phase locked loop 649. Loop 649, which serves as bandpass filter and signal conditioner, sends a square wave signal to edge trigger flip flop 651. The second signal output (LOCK) serves to indicate whether loop 649 is locked onto a valid signal input or not.

The lowest priority interrupt signal, Real Time Clock signal 643, is generated by register 621. Register 621 which is loaded and stored by memory reference instructions from CPU module 500 is decremented by a clock signal in line 643 which may be derived from I/O Module clock 570. On the register count reaching zero, register 621 sends an interrupt signal to edge trigger flip flop 656. A spare interrupt 642 is also provided.

Setting of one or more of the edge trigger flip flops 647, 651, 654, 656 by the interrupt signals 640, 641, 642, 643 generates a signal (INT) via priority chip 659 to processor 542 of CPU Module 500. On acknowledgement, processor 542, issues a signal (INTA) transferring the status of the edge trigger flip flops 647, 651, 654, 656 to a four bit latch 660 to generate an interrupt instruction code (RESTART) onto the data bus 508.

Each interrupt is assigned a unique RESTART instruction code. Should an interrupt of higher priority be triggered, a new interrupt signal (INT) and RESTART

instruction code are generated resulting in a nesting of interrupt software routines whenever the interrupt recognition circuitry is enabled within the CPU 500.

Priority chip 659 serves to establish a handling priority in the event of simultaneous interrupt signals in accordance with the priority schedule described.

Once triggered, the edge trigger flip flop 647, 651, 654 or 656 must be reset in order to capture the next occurrence of the interrupt associated therewith. Each interrupt subroutine serves, in addition to performing the functions programmed, to reset the flip flops (through the writing of a coded byte in a uniquely selected address) and to re-enable the interrupt (through execution of a re-enabling instruction). Until reenabled, initiation of a second interrupt is precluded while the first interrupt is in progress.

Lines 658 permit interrupt status to be interrogated by CPU module 500 on a memory reference instruction.

I/O Module 502 includes a suitable pulse generator or clock 570 for generating the various timing signals required by module 502. Clock 570 is driven by the pulse-like output $\phi_1 - 1$, $\phi_2 - 1$ of processor clock 522 (FIG. 19a). As described, clock 570 provides a reference clock pulse (in line 574) for synchronizing the output refresh data and is the source of clock pulses (in line 643) for driving Real Time register 621.

CPU interface module 504 interfaces I/O module 502 with the host machine 10 and transmits operating data stored in RAM section 546 to the machine. Referring particularly to FIGS. 25 and 26, data and address information are inputted to module 504 through suitable means such as optical type couplers 700 which convert the information to single ended logic levels. Data in bus 508 on a signal from Refresh Control 605 in line 607 (LOAD), is clocked into module 546 at the reference clock rate in line 574 parallel by bit, serial by byte for a preset byte length, with each data bit of each successive byte being clocked into a separate data channel D0-D7. As best seen in FIG. 25, each data channel D0-D7 has an assigned output function with data channel D0 being used for operating the front panel lamps 830 in the digital display, (see FIG. 32), data channel D1 for special circuits module 522, and remaining data channels D2-D7 allocated to the host machine operating sections 530, 532, 534, 536, 538 and 540. Portions of data channels D1-D7 have bits reserved for front panel lamps and digital display.

Since the bit capacity of the data channels D2-D7 is limited, a bit buffer 703 is preferably provided to catch any bit overflow in data channels D2-D7.

Inasmuch as the machine output sections 530, 532, 534, 536, 538 and 540 are electrically a long distance away, i.e. remote, from CPU interface module 504, and the environment is electrically "noisy," the data stream in channels D2-D7 is transmitted to remote sections 530, 532, 534, 536, 538 and 540 via a shielded twisted pair 704. By this arrangement, induced noise appears as a differential input to both lines and is rejected. The associated clock signal for the data is also transmitted over line 704 with the line shielded carrying the return signal currents for both data and clock signals.

Data in channel D₁, destined for special circuits module 522 is inputted to shift register type storage circuitry 705 for transmittal to module 522. Data is also inputted to main panel interface module 526. Address information in bus 507 is converted to single ended output by couplers 700 and transmitted to Input Matrix Module 524 to address host machine inputs.

CPU interface module 504 includes fault detector circuitry 706 for monitoring both faults occurring in host machine 10 and faults or failures along the buses, the latter normally comprising a low voltage level or failure in one of the system power lines. Machine faults may comprise a fault in CPU module 500, a belt mis-track signal from sensor 27 (see FIG. 2), opening one of the machine doors or covers as responded to by conventional cover interlock sensors (not shown), a fuser over temperature as detected by sensor 175, etc. In the event of bus fault, a reset signal (RESET) is generated automatically in line 709 to CPU module 500 (see FIGS. 17 and 18) until the fault is removed. In the event of a machine fault, a signal is generated by the CPU in line 710 to actuate a suitable relay (not shown) controlling power to all or a portion of host machine 10. A load disabling signal (LOAD DISBL) is inputted to optical couplers 700 via line 708 in the event of a fault in CPU module 500 to terminate input of data to host machine 10. Other fault conditions are monitored by the software background program. In the event of a fault, a signal is generated in line 711 to the digital display on control console 800 (via main panel interface module 526) signifying a fault.

Referring particularly to FIGS. 25 and 27, special circuits module 522 comprises a collection of relatively independent circuits for either monitoring operation of and/or driving various elements of host machine 10. Module 522 incorporates suitable circuitry 712 for amplifying the output of sensors 225, 226, 227, 228 and 280, 281, 282 of sorter 14 and document handler 16 respectively; circuitry 713 for operating fuser release clutch 159; and circuitry 714 for operating main and auxiliary paper tray feed roll clutches 130, 131 and document handler feed clutch 244.

Additionally, fuser detection circuitry 715 monitors temperature conditions of fuser 150 as responded to by sensor 174. On overheating of fuser 150, a signal (FUS-OT) is generated to turn heater 163 off, actuate clutch 159 to separate fusing and pressure rolls 160, 161; trigger trap solenoid 158 to prevent entrance of the next copy sheet into fuser 150, and initiate a shutdown of host machine 10. Circuitry 715 also cycles fuser heater 163 to maintain fuser 150 at proper operating temperatures and signals (FUS-RDUT) host machine 10 when fuser 150 is ready for operation.

Circuitry 716 provides closed loop control over sensor 98 which responds to the presence of a copy sheet 3 on belt 20. On a signal from sensor 98, solenoid 97 is triggered to bring deflector 96 into intercepting position adjacent belt 20. At the same time, a backup timer (not shown) is actuated. If the sheet is lifted from the belt 20 by deflector 96 within the time allotted, a signal from sensor 99 disables the timer and a missstrip type jam condition of host machine 10 is declared and the machine is stopped. If the signal from sensor 99 is not received within the allotted time, a sheet on selenium (SOS) type jam is declared and an immediate machine stop is effected.

Circuitry 718 controls the position (and hence the image reduction effected) by the various optical elements that comprise main lens 41 in response to the reduction mode selected by the operator and the signal inputs from lens position responsive sensors 116, 117, 118. The signal output of circuitry 718 serves to operate lens drive motor 43 as required to place the optical elements of lens 41 in proper position to effect the image reduction programmed by the operator.

Referring to FIG. 28, input matrix module 524 provides analog gates 719 for receiving data from the various host machine sensors and inputs (i.e. sheet sensors 135, 136; pressure sensor 157; etc), module 524 serving to convert the signal input to a byte oriented output for transmittal to I/O module 502 under control of Input Matrix Select 604. The byte output to module 524 is selected by address information inputted on bus 507 and decoded on module 524. Conversion matrix 720, which may comprise a diode array, converts the input logic signals of "0" to logic "1" true. Data from input matrix module 524 is transmitted via optical isolators 721 and Input Matrix Select 604 of I/O module 502 to CPU Module 500.

Referring particularly to FIG. 29, main panel interface module 526 serves as interface between CPU interface module 504 and operator control console 800 for display purposes and as interface between input matrix module 524 and the console switches. As described, data channels D0-D7 have data bits in each channel associated with the control console digital display or lamps. This data is clocked into buffer circuitry 723 and from there, for digital display, data in channels D1-D7 is inputted to multiplexer 724. Multiplexer 724 selectively multiplexes the data to HEX to 7 segment converter 725. Software controlled output drivers 726 are provided for each digit which enable the proper display digit in response to the data output of converter 725. This also provides blanking control for leading zero suppression or inter digit suppression.

Buffer circuitry 723 also enables through anode logic 728 the common digit anode drive. The signal (LOAD) to latch and lamp driver control circuit 729 regulates the length of the display cycle.

For console lamps 830, data in channel D0 is clocked to shift register 727 whose output is connected by drivers to the console lamps. Access by input matrix module 524 to the console switches and keyboard is through main panel interface module 526.

The machine output sections 530, 532, 534, 536, 538, 540 are interfaced with I/O module 502 by CPU interface module 504. At each interrupt/refresh cycle, data is outputted to sections 530, 532, 534, 536, 538, 540 at the clock signal rate in line 574 over data channels D2, D3, D4, D5, D6, D7 respectively.

Referring to FIG. 30, wherein a typical output section i.e. document handler section 530 is shown, data inputted to section 530 is stored in shift register/latch circuit combination 740, 741 pending output to the individual drivers 742 associated with each machine component. Preferably d.c. isolation between the output sections is maintained by the use of transformer coupled differential outputs and inputs for both data and clock signals and a shielded twisted conductor pair. Due to transformer coupling, the data must be restored to a d.c. waveform. For this purpose, control recovery circuitry 744, which may comprise an inverting/non-inverting digital comparator pair and output latch is provided.

The LOAD signal serves to lockout input of data to latches 741 while new data is being clocked into shift register 740. Removal of the LOAD signal enables commutation of the fresh data to latches 741. The LOAD signal also serves to start timer 745 which imposes a maximum time limit within which a refresh period (initiated by Refresh Control 605) must occur. If refresh does not occur within the prescribed time limit, timer 745 generates a signal (RESET) which sets shift register 740 to zero.

With the exception of sorter section 534 discussed below, output sections 532, 536, 538 and 540 are substantially identical to document handler section 530.

Referring to FIG. 31 wherein like numbers refer to like parts, to provide capacity for driving the sorter deflector solenoids 217, a decode matrix arrangement consisting of a Prom encoder 750 controlling a pair of decoders 751, 752 is provided. The output of decoders 751, 752 drive the sorter solenoids 217 of upper and lower bin arrays 210, 211 respectively. Data is inputted to encoder 750 by means of shift register 754.

Referring now to FIG. 32, control console 800 serves to enable the operator to program host machine 10 to perform the copy run or runs desired. At the same time, various indicators on console 800 reflect the operational condition of machine 10. Console 800 includes a bezel housing 802 suitably supported on host machine 10 at a convenient point with decorative front or face panel 803 on which the various machine programming buttons and indicators appear. Programming buttons include power on/off buttons 804, start print (PRINT) buttons 805, stop print (STOP) button 806 and keyboard copy quantity selector 808. A series of feature select buttons consisting of auxiliary paper trap button 810, two sided copy button 811, copy lighter button 814, and 25 copy darker button 815, are provided.

Additionally, image size selector buttons 818, 819, 820; multiple or single document select buttons 822, 823 for operation of document handler 16; and sorter sets or stacks buttons 825, 826 are provided. An on/off service selector 828 is also provided for activation during machine servicing.

Indicators comprise program display lamps 830 and displays such as READY, WAIT, SIDE 1, SIDE 2, ADD PAPER, CHECK STATUS PANEL, PRESS 35 FAULT CODE, QUANTITY COMPLETED, CHECK DOORS, UNLOAD AUX TRAY, CHECK DOCUMENT PATH, CHECK PAPER PATH, JOB INCOMPLETE and UNLOAD SORTER. Other display information may be envisioned.

MACHINE OPERATION

As will appear, host machine 10 is conveniently divided into a number of operational states. The machine control program is divided into background routines 45 and Foreground routines with operational control normally residing in the Background routine or routines appropriate to the particular machine state then in effect. The output buffer 546 of RAM memory section 546 is used to transfer/refresh control data to the various remote locations in host machine 10, control data from both Background and Foreground routines being inputted to buffer 546 for subsequent transmittal to host machine 10. Transmittal/refresh of control data presently in output buffer 546 is effected through Direct 55 Memory access (DMA) under the aegis of a Machine Clock interrupt routine.

Foreground routine control data which includes a Run Event Table built in response to the particular copy run or runs programmed, is transferred to output buffer 546 by means of a multiple prioritized interrupt system wherein the Background routine in process is temporarily interrupted while fresh Foreground routine control data is inputted to buffer 546 following which the interrupted Background routine is resumed.

The operating program for host machine 10 is divided into a collection of foregoing tasks, some of which are driven by the several interrupt routines and

background or non-interrupt routines. Foreground tasks are tasks that generally require frequent servicing, high speed response, or synchronization with the host machine 10. Background routines are related to the state of host machine 10, different background routines being performed with different machine states. A single background software control program (STCK) composed of specific sub-programs associated with the principal operating states of host machine 10 is provided. A byte called STATE contains a number indicative of the current operating state of host machine 10. The machine STATES are as follows:

STATE NO.	MACHINE STATE	CONTROL SUBR.
0	Software Initialize	INIT
1	System Not Ready	NRDY
2	System Ready	RDY
3	Print	PRINT
4	System Running, Not Print	RUNNPRT
5	Service	TECHREP

Referring to FIG. 33, each STATE is normally divided into PROLOGUE, LOOP and EPILOGUE sections. As will be evident from the exemplary program STCK reproduced in TABLE I, entry into a given STATE (PROLOGUE) normally causes a group of operations to be performed, these consisting of operations that are performed once only at the entry into the STATE. For complex operations, a CALL is made to an applications subroutine therefor. Relatively simpler operations (i.e. turning devices on or off, clearing memory, presetting memory, etc.) are done directly.

Once the STATE PROLOGUE is completed, the main body (LOOP) is entered. The program (STCK) remains in this LOOP until a change of STATE request is received and honored. On a change of STATE request, the STATE EPILOGUE is entered wherein a group of operations are performed, following which the STATE moves into the PROLOGUE of the next STATE to be entered.

Referring to FIG. 34 and the exemplary program (STCK) in TABLE I. On actuation of the machine POWER-ON button 804, the software Initialize STATE (INIT) is entered. In this STATE, the controller is initialized and a software controlled self test subroutine is entered. If the self test of the controller is successfully passed, the System Not Ready STATE (NRDY) is entered. If not, a fault condition is signaled.

In the System Not Ready STATE (NRDY), background subroutines are entered. These include setting of Ready flags, control registers, timers, and the like; turning on power supplies, the fuser, etc., initializing the Fault Handler, checking for paper jams (left over from a previous run), door and cover interlocks, fuser temperatures, etc. During this period, the WAIT lamp on console 800 is lit and operation of host machine 10 precluded.

When all ready conditions have been checked and found acceptable, the controller moves to the system ready state (RDY). The READY lamp on console 800 is lit and final ready checks made. Host Machine 10 is now ready for operation upon completion of input of a copy run program, loading of one or more originals 2 into document handler 16 (if selected by the operator), and actuation of START PRINT button 805. As will appear hereinafter, the next state is PRINT wherein the particular copy run programmed is carried out.

While the machine is completing a copy run, the controller normally enters the Run Not Print state (RUNNPRNT) where the controller calculates the number of copies delivered, resets various flags, stores certain machine event information in the memory, as well as generally conditioning the machine for another copy run, if desired. The controller then returns to the System Not Ready state (NRDY) to recheck for ready conditions preparatory for another copy run, with the same state sequence being repeated until the machine is turned off by actuation of POWER OFF button 804 or a malfunction inspired shutdown is triggered. The last state (TECH REP) is a machine servicing state wherein certain service routines are made available to the machine/repair personnel, i.e. Tech Reps.

Referring particularly to FIG. 32 and Tables II, III, IV, V, VI and VII, the machine operator uses control console 800 to program the machine for the copy run desired. Programming may be done during either the System Not Ready (NRDY) or System Ready (RDY) states, although the machine will not operate during the System Not ready state should START PRINT button 805 be pushed. The copy run includes selecting (using keyboard 808) the number of copies to be made, and such other ancillary program features as may be desired, i.e. use of auxiliary paper tray 102, (push button 810), image size selection (push buttons 818, 819, 820), document handler/sorter selection (push buttons 822, 823, 825, 826), copy density (push buttons 814, 815), duplex or two sided copy button 811, etc. On completion of the copy run program, START PRINT button 805 is actuated to start the copy run programmed (presuming the READY lamp is on and an original or originals 2 have been placed in tray 233 of document handler 16 if the document handler has been selected).

With programming of the copy run instructions, controller 18 enters a Digit Input routine in which the program information is transferred to RAM section 546. The copy run program data passes via Main Panel Interface Module 526 to Input Matrix Module 524 and from there is addressed through Matrix Input Select 604, Multiplexer 624, and Buffers 620 of I/O Module 502 to RAM section 546 of CPU Module 500.

On entering PRINT STATE, a Run Event Table (FIG. 35) comprised of Foreground tasks is built for operating in cooperation with the background tasks the various components of host machine 10 in an integrated manner to produce the copies programmed. The run Event Table is formed by controller 18 through merger of a Fixed Pitch Event Table (TABLE II) (stored in ROM 545 and Non Volatile Memory 610) and a Variable Pitch Event Table (TABLE III) in a fashion appropriate to the parameters of the job selected.

The fixed Pitch Event Table (TABLE II) is comprised of machine events whose operational timing is fixed during each pitch cycle such as the timing of bias to transfer roll 75, (TRN 2 CURR), actuating toner concentration sensor 65 (ADC ACT), loading roll 161 of fuser 150 FUS*LOAD), and so forth, irrespective of the particular copy run programmed. The Variable Pitch Table (TABLE III) is comprised of machine events whose operational timing varies with the individual copy run programmed, i.e. timing of pitch fade-out lamp 44 (FO*ONBSE) and timing of flash illumination lamps 37 (FLSH BSE). The variable Pitch Table is built by the Pitch Table Builder (TABLE IV) from the copy run information programmed in by controller 18 (using the machine control program stored in ROM

section 545 and Non-Volatile Memory 610), coupled with event address information from ROM section 545, sorted by absolute clock count (via the routine shown in TABLE V), and stored in RAM section 546 (via the routine shown in TABLE VI). The Fixed Pitch Event Table and Variable Pitch Table are merged with the relative clock count differences between Pitch events calculated to form a Run Event Table (TABLE VII).

Referring particularly to FIG. 35, the Run Event Table consists of successive groups of individual events 851. Each event 851 is comprised of four data blocks, data block 852 containing the number of clock pulses (from machine 202) to the next scheduled pitch event (REL DIFF), data block 853 containing the shift register position associated with the event (REL SR), and data blocks 854, 855 (EVENT LO) (EVENT HI) containing the address of the event subroutine.

In machine states other than PRINT, data blocks 852, 853 (REL DIFF) (REL SR) are set to zero. Data blocks 854, 855 hold the address information for the Non-Print state event.

Control Data in the Run Event Table represents a portion of the foreground tasks and is transferred to the output buffer 546' of RAM memory section 546 by the Pitch Reset and Machine Clock interrupt routines. Other control data, representing foreground tasks not in the Run Event Table is transferred to RAM output buffer 546' by the Real Time Clock interrupt routine. Transfer of the remainder of the control data to output buffer 546' is by means of background (non-interrupt) routines.

Transfer of control data from output buffer 546' of RAM memory section 546 to the various locations in host machine 10 is through output Refresh via Direct Memory access (DMA) in response to machine clock interrupt signals as will appear. The interrupt routines are initiated by the respective interrupt signals.

Referring particularly to FIGS. 23 and 35-37 and TABLES VII, VIII the interrupt having the highest priority, the Pitch Reset interrupt (signal 640), is operable only during the PRINT state, and occurs once each revolution of sheet register fingers 141 as responded to by sensor 146 of pitch reset clock 138. At each pitch reset interrupt signal, after a determination of priority by Priority Chip 659 in the event of multiple interrupt signals, as interrupt signal (INT) is generated. The acknowledgement signal (INTA) from processor 542 initiates the pitch reset interrupt routine.

On entering the pitch reset routine, the interrupt is re-enabled and the contents of the program working registers stored. A check is made to determine if building of the Run Event Table is finished. Also checks are made to insure that a new shift register schedules have been built and at least 910 clock counts since the last pitch reset have elapsed. If not, an immediate machine shutdown is initiated.

Presuming that the above checks are satisfactory, the shift register pointer (SR PTR), which is the byte variable containing the address of a pre-selected shift register position (SR O), is decremented by one and adjusted for overflow and the shift register contents are updated with a byte variable (SR + VALUV) containing the new shift register value to be shifted in following the pitch reset interrupt. The event pointer (EV*PTR), a two byte variable containing the full address of the next scheduled event, is reset to Event #1. The count in the C register equals the time of the first event.

Machine Cycle Down, Normal Down, and Side One Delay checks are made, and if negative, the count on a cycle up counter (CYC UP CT) is checked. If the count is less than a predetermined control count (i.e. 5), the counter (CYC UP CT) is incremented by one. When the count on the cycle up counter equals the control count, and Image Made Flag is set.

If a Normal Down, Cycle Down, or Side One Delay has been initiated, the cycle up counter (CYC UP CT) is reset to a preset starting count (i.e. 2). The pitch reset interrupt routine is exited with restoration of the working registers and resetting of pitch reset flip flop 647.

The Machine Clock Interrupt routine, which is second in priority, is operative in all operational states of host machine 10. Although nominally driven by machine clock 202, which is operative only during Print state when processor main drive motor 34 is energized, machine clock pulses are also provided by phase locked loop 649 when motor 34 is stopped.

Referring particularly to FIG. 38 and TABLE IX, entry to the Machine Clock interrupt there shown is by a signal (INTA) from processor 542 following a machine clock interrupt signal 642 as described earlier. On entry, the event control register (C REG) is obtained and the working register contents stored. The C REG is decremented by one, the register having been previously set to a count corresponding to the next event in the Event Run Table.

The control register (C REG) is checked for zero. If the count is not zero and is an odd number, an output refresh cycle is initiated to effect transfer/refresh of data in RAM output buffer 546' to host machine 10. If the number is even, or following an output refresh, the interrupt system is re-enabled, the machine clock interrupt flip flop 651 is reset and the working registers are restored. Return is then made to the interrupted routine.

If the control register (C REG) count is zero, the Event Pointer (EV*PTR), which identifies the clock count (in data block 852) for the next scheduled event (REL DIFF), is loaded and the control register (C REG) reset to a new count equal to the time to the next event. The Event Pointer (EV*PTR) is incremented to the relative shift register address for the event (REL SR, data block 853), and the shift register address information is set in appropriate shift registers (B, D, E, A registers).

The event Pointer (EV*PTR) is incremented successively to the event subroutine address information (EVENT LO) (EVENT HI) in the Event Run Table, and the address information therefrom loaded into a register pair (D & E registers). The Event Pointer (EV PTR) is incremented to the first data block (REL DIFF) of the next succeeding event in the Run Event Table, saved, and the register pair (H & L registers) that comprise the Event Pointer are loaded with the event subroutine address from the register pair (D & E registers) holding the information. The register pair (D & E registers) are set to the return address for the Event Subroutine. Using the address information, the Event Subroutine is called and the subroutine data transferred to RAM output buffer 546' for transfer to the host machine on the next Output Refresh.

Following this, the Machine Clock interrupt routine is exited as described earlier.

The Output Refresh cycle alluded to earlier functions, when entered, to transfer/refresh data from the output buffer of 546' RAM section 546 to host machine

10. Direct Memory Access (DMA) is used to insure a high data transfer rate.

5 On a refresh, Refresh Control 605 (see FIG. 23) raises the HOLD line to processor 542, which on completion of the operation then in progress, acknowledges by a HOLD A signal. With processor 542 in a hold mode and Address and Data buses 507, 508 released to I/O Module 502 (through operation of tri-state buffers 510, 511, 563, 570), the I/O module then sequentially accesses the output buffer 546' of RAM section 546 and transfers the contents thereof to host machine 10. Data previously transferred is refreshed.

15 The Real Time Interrupt, which carries the lowest priority, is active in all machine states. Primarily, the interrupt acts as an interval timer by decrementing a series of timers which in turn serve to control initiation of specialized subroutines used for control and error checking purposes.

20 Referring particularly to FIG. 39 and TABLE X, the Real Time interrupt routine is entered in the same manner as the interrupt routines previously described, entry being in response to a specific RESTART instruction code assigned to the Real Time interrupt. On entry, the interrupt is re-enabled and the register contents stored. The timer pointer (PNTR) for the first class of timers (i.e. 10 msec TIMERS) is loaded, and a loop counter identifying the number of timers of this class (i.e. 10 msec TIMERS) preset. A control register (E REG) is loaded and a timer decrementing loop is entered for the first timer. The loop decrements the particular timer, increments the timer pointer (PNTR) to the location of the next timer in this class, checks the timer count, and decrements the loop counter. The decrementing loop routine is repeated for each timer in the class (i.e. 10 msec TIMERS) following which a control counter (CNTR) for the second group of timers (i.e. 100 msec TIMERS) is decremented by one and the count checked.

25 30 35 40 45 40 The control counter (CNTR) is initially set to a count equal to the number of times the first timer interval is divisible into the second timer interval. For example, if the first class of timers are 10 msec timers and the second timer class are 100 msec timers, the control counter (CNTR) is set at 10 initially and decremented on each Real Time interrupt by one down to zero.

50 55 If the count on the control counter (CNTR) is not zero, the registers are restored, Real Time interrupt flip flop 856 reset, and the routine exited. If the count on the control counter is zero, the counter is reloaded to the original maximum count (i.e. 10) and a loop is entered decrementing individually the second group of timers (i.e. 100 msec TIMERS). On completion, the routine is exited as described previously.

In the following TABLES:

60 “@” — is used to indicate flags, counters and subroutine names.

“#” — is used to indicate input signals.

“\$” — is used to indicate output signals.

“.” — is used to indicate macro instructions, system subroutines, system flags, and data, etc.

65 For further explanation of the mnemonics and particular instructions utilized by the following routines, the reader is directed to Intel Corporation's Programming Manual for the 8080 Microcomputer System.

Referring particularly to the timing chart shown in FIG. 40, an exemplary copy run wherein three copies of each of two simplex or one-sided originals in duplex mode is made. Referring to FIG. 32, the appropriate button of copy selector 808 is set for the number of copies desired, i.e. 3 and document handler button 822, sorter select button 825 and two sided (duplex) button 811 depressed. The originals, in this case, two simplex or one-sided originals are loaded into tray 233 of document handler 16 (FIG. 14) and the Print button 805 depressed. On depression of button 805, the host machine 10 enters the PRINT state and the Run Event Table for the exemplary copy run programmed is built by controller 18 and stored in RAM section 546. As described, the Run Event Table together with Background routines serve, via the multiple interrupt system and output refresh (through D.M.A.) to operate the various components of host machine 10 in integrated timed relationship to produce the copies programmed.

During the run, the first original is advanced onto platen 35 by document handler 16 where, as seen in FIG. 41, three exposures (1ST FLASH SIDE 1) are made producing three latent electrostatic images on belt 20 in succession. As described earlier, the images are developed at developing station 28 and transferred to individual copy sheets fed forward (1ST FEED SIDE 1) from main paper tray 100. The sheets bearing the images are carried from the transfer roll/belt nip by vacuum transport 155 to fuser 150 where the images are fixed. Following fusing, the copy sheets are routed by deflector 184 (referred to as an inverter gate in the tables) to return transport 182 and carried to auxiliary tray 102. The image bearing sheets entering tray 102 are aligned by edge pattern 187 in preparation for refeeding thereof.

Following delivery of the last copy sheet to auxiliary tray 102, the document handler 16 is activated to remove the first original from platen 35 and bring the second original into registered position on platen 35. The second original is exposed three times (FLASH SIDE 2), the resulting images being developed on belt 20 at developing station 28 and transferred to the opposite or second side of the previously processed copy sheets which are now advanced (FEED SIDE 2) in timed relationship from auxiliary tray 102. Following transfer, the side two images are fused by fuser 150 and

routed, by gate 184 toward stop 190, the latter being raised for this purpose. Abutment of the leading edge of the copy sheet with stop 190 causes the sheet trailing edge to be guided into discharge chute 186, effectively inverting the sheet, now bearing images on both sides.

30 The inverted sheet is fed onto transport 181 and into an output receptacle such as sorter 14 where, in this example, the sheets are placed in successive ones of the first three trays 212 of either the upper or lower arrays 201, 211 respectively depending on the disposition of deflector 220.

35

JOB RECOVERY

Referring now to FIGS. 41-45, there will be described in more detail the method of controlling machine 10 to produce duplex copies from a set of original documents and for automatically adjusting the reproduction process in the event of a fault condition so that the selected number of copies are ultimately produced even though some copies may have been lost due to the fault.

45 Referring especially to FIG. 41, it will be remembered that the controller 18 is normally being instructed by the state checker or master program which is shown in Table I. Before the beginning of a copy run, the controller 18 fetches the input data for the particular copy run, such as the quantity of copies selected (QTY@SEL), whether the document handler 16 has been selected (ADH@MSEL), the condition of the sorter 14, 50 e.g. whether both bin arrays 210 and 211 are empty (TWO@AVAL), whether duplex copies are desired (2SD@FLAG), etc. As is well known in the art, controller 18 has previously set the appropriate flags (as set out in the parentheses above) when the user has selected 55 the various machine features by pressing the corresponding console buttons on console 800, or, as in the case of the sorter 14, by the condition of sensors (e.g. 225, 226) detecting the condition of the machine.

60 Before the copy run is initiated, controller 18 is instructed to utilize this copy run data to calculate the set quantity (QTY@SET). The set quantity is the number of copies that can be made without exceeding the capacity of the machine. For example, if one of the bin arrays 210, 211 is empty, the capacity of the sorter 14 is 25 collated books. If the quantity selected is greater than

25, the job must be broken down into sets of 25 copies or less. This is accomplished by the set prediction routine (MODE @ reproduced in Table XI) which is called by the State Checker routine. This routine also calculates and stores the quantity to be flashed (QTY @TBF) and quantity to be delivered (QTY @TBD) for each original. In this embodiment, these stored quantities are placed in RAM memory 546 by means well known in the art. For purposes of illustration, assume that 100 collated duplex copies have been selected and that one of the sorter bin arrays is empty. This routine fetches the stored capacity of sorter 14 for making collated books with one bin array empty. This capacity is compared with the quantity selected. Since the quantity selected exceeds the capacity of the machine for this copy run, controller 18 will divide it into a plurality of sets of 25 each. Consequently, the quantity to be flashed (QTY @TBF) and delivered (QTY @TBD) would likewise be 25 and would be stored in a memory location. In comparison, if 100 non-collated copies (STACKS) are selected, the sorter's capacity would not be exceeded and the copy run can proceed with the set quantity, quantity to be flashed, and quantity to be delivered all being 100. It should be noted that while the subject invention is described in connection with a machine utilizing flash exposure, other types of exposure techniques can also be utilized, such as known scanning techniques including laser beam exposure. It should also be realized that while the quantity to be delivered for each original will be the same, the copies of the originals may be delivered to different places within the machine. For example, side 1 copies will be delivered to auxiliary tray 102, while the finished side 2 or duplex copies will be delivered to sorter 14.

The set prediction routine also clears the necessary counters etc. prior to the copy run. When the machine parameters indicates that the machine is ready to make copies, it enters the PRINT state as described earlier herein.

Referring now especially to FIG. 42, the document handler 16 is cycled to place the side 1 original on platen 35. For purposes of this invention, a side 1 original means an original document 2 or representations thereof from which images are formed to produce copies on the front side or side 1 of copy sheets 3. Similarly, a side 2 original means an original document 2 or representations thereof from which images are made to form copies on the back side or side 2 of copy sheets 3 bearing side 1 copies on their opposite sides. The machine includes a provision for indicating whether it is making side 1 or side 2 copies. For example, controller 18 sets a flag SD1 DEL when it is making copies from side 1 originals. This flag is then cleared as soon as all of the side 1 copies are delivered. The flag is reset when all of the side 2 or duplex copies have been successfully delivered. In the event of a fault condition, controller 18 checks the status of this flag to determine what copies must be remade. For example, if the flag is set at the time of the fault, only side 1 copies must be recovered or remade. On the other hand, both side 1 and side 2 copies must be remade if the flag is not set at the time of the fault. The procedure for automatically remaking the necessary lost copies due to the fault will now be explained.

The side 1 original is exposed by activating flash lamps 37 (see, e.g. FIG. 2) of the illumination assembly thereby forming images thereof on photoreceptor belt

20. A quantity flashed counter (QTY @FLH) maintains a running count of the number of flashes made for each original. The quantity flashed counter is a software counter, as are the remaining counters referred to in this description. A software counter is well known in the art and as such forms no part of this invention. Typically, such counters are memory locations which are incremented by appropriate signals, for example, in the case of the quantity flashed counter, by a signal generated everytime flash lamps 37 are activated. In the absence of a fault condition, flashing of the side 1 original continues until there is flash coincidence. Flash coincidence is met when the stored quantity to be flashed (QTY @TBF) is the same as the contents of the quantity flashed counter (QTY @FLH). In this embodiment, this is accomplished by the instructions provided by the flash increment routine (FLASHINC) reproduced in Table XII. As soon as there flash coincidence, the flash lamps 37 are deactivated. However, the side 1 original remains on the platen until there is delivery coincidence as well. As previously described, side 1 copies are inverted and routed back into a temporary receptacle or auxiliary tray 102. Appropriate sensors, such as sensor 189 detects the entry of successfully completed side 1 copies into auxiliary tray 102 as can be seen most clearly in FIG. 12. The output of sensor 189 is coupled to a copies delivered counter (QTY @DLV) which maintains a running count of the number of successfully delivered copies, be it side 1 copies to auxiliary 102 or side 2 copies to sorter 14 as similarly detected by sensors 225 or 226 for sorter bin arrays 210, 211, respectfully. A delivery increment routine (OUT @INC reproduced in Table XIX) increments and compares the contents of the copies delivered counter (QTY @DLV) with the predicted quantity to be delivered (QTY @TBD) necessary for proper completion of the copy run.

After side 1 flash and delivery coincidences are both met, the side 1 original is removed from platen 35 and returned to paper tray 233 on top of bail bar 235 (see FIG. 14). Every time an original document is removed from platen 35, an originals flashed counter (ORIG @FLH) is incremented by routines REVERSE and INC @ORFH reproduced in Tables XIV and XV, respectively. Similarly, whenever there is delivery coincidence, an originals delivered counter (ORIG @DLV) is incremented thereby keeping a running count of the number of originals from which all the necessary copies have been made.

Controller 18 then checks to determine if there are any more originals to be placed on the platen 35. This may be accomplished by the input empty routine (LEDGIEMP reproduced in Table XVI). Briefly, when the last original leaves tray 235, bail bar or separate 235 contacts switch 259 thereby signalling that the last original has left the tray 233. After the last original has been placed on platen 35 and exposed, the controller compares the stored quantity of selected copies (QTY @SEL) with the quantity of flashes made (QTY @FLH). If, for example, the number of copies selected is greater than the number of flashes made document handler 16 is recycled to refeed the originals to platen 35 beginning with the first original, with the machine completing the job by making the necessary copies. As noted before, this will occur when the job has been split up into multi-set copy runs since the quantity flashed (QTY @FLH) will be less than the quantity selected when the set quantity is less than the quantity selected (QTY @SEL).

Assuming that the side 1 original was not the last original, the next original, here, the side 2 original is placed on platen 35. Flash lamps 37 are then activated until there is exposure coincidence, i.e. the number of flashes actually made as indicated by the quantity flashed counter (QTY@FLH) is the same as the quantity to be flashed (QTY@TBF). Unlike the side 1 original, the side 2 original is removed from platen 35 and the succeeding document, here the next side 1 original (e.g. page 3), is placed on platen 35 as soon as there is side 2 exposure coincidence. It should be realized that there is a significant delay between the time of exposure and the time of delivery of the copies made from the exposed original. For example, the necessary number of side 2 exposures may be completed before the side 2 or duplex copies have been delivered to sorter 14. As described earlier, the side 2 copies are formed on the opposite sides of the side 1 copies fed from auxiliary tray 102. Hence, by activating the document handler 16 to place the next side 1 original on platen 35 in preparation for making copies therefrom, the throughput of the machine is thereby optimized. In fact, exposure of the next side 1 original can be begun before the last duplex copy has been delivered to sorter 14. After there is side 2 delivery coincidence, the originals delivered counter (ORIG@DLV) is incremented and the above described sequence is repeated until the necessary copies are made.

It is a feature of the invention that none of the side 2 originals are presented to the machine processor 12 until there is both side 1 flash and delivery coincidences. This permits controller 18 to readily keep track of the number of copies made and their location with only a minimal number of counting devices, sensors, etc. On the other hand, the machine is conditioned to receive 35 images from the next side 1 original as soon as there is flash coincidence for the side 2 original thereby optimizing the speed of the machine. Moreover, this sequence of events permits controller 18 to initiate the necessary recovery steps to remake lost copies in the 40 event of a fault condition. These recovery steps will differ depending upon the event currently in process at the time of the fault condition. These fault conditions represent a wide variety of machine malfunctions and include such things as paper jams which are detected by sensors disposed along the machine paper path as is well known in the art. When a fault condition is detected, the sensors send appropriate signals to controller 18 which enters the Run Not Print STATE and ceases further machine operation. In this STATE, controller 18 is 45 instructed by the Delivery Check (DEL@CK) routine reproduced in Table XIII. This routine determines whether there has been side 1 or side 2 delivery coincidence at the time of the fault. If not, it initiates the recovery steps for remaking any copies lost due to the 50 fault as described below.

Since the side 1 original is not removed from platen 35 until there is both flash and delivery coincidence, controller 18 realizes that the correct original for remaking any lost copies is still on the platen when there is a fault before side 1 flash or delivery coincidence. Turning to FIG. 43, in the event of a side 1 fault the operator is instructed to remove the side 1 copies from the paper path. In other words, all of the copies sheets 3 in transit to the auxiliary tray 102 are considered lost. However, some of the side 1 copies may have been successfully delivered to the auxiliary tray 102. This would be indicated by the contents of the copies deliv-

ered counter (QTY@DLV). Under instruction of the flash increment routine (FLASHINC), the quantity flashed counter (QTY@FLH) is reset with the contents of the copies delivered counter (QTY@DLV). For 5 purposes of illustration assume that 10 copies were selected, but that only three copies were actually delivered to auxiliary tray 102 before the fault occurred. Then, even though there may have been side 1 flash coincidence, the quantity flash counter (QTY@FLH) would be reset with the number 3. The side 1 original, which is already on the platen, would be exposed seven additional times to remake the lost copies. As soon as there is delivery coincidence, the side 2 original would be placed on the platen and the normal sequence of events shown in FIG. 42 would take place in order to finish the copy run.

Assume now that the fault, instead, occurs after side 1 delivery coincidence but before there is side 2 delivery coincidence. Again, due to the preset sequence of 20 operation, the correct original for recovering lost copies will still be on platen 35 if side 2 flash coincidence has not been met. As described earlier herein, the side 2 original is not removed from platen 35 until there is flash coincidence. Consequently, the contents of the originals flashed (ORIG@FLH) counter is the same as the originals delivered (ORIG@DLV) counter. The Delivery Check routine calls a routine (RECOV@CK) which senses this coincidence thereby signalling that the correct original is still on the platen. However, since 25 it is a side 2 fault some of the side 1 copies must be remade even though they were successfully delivered to auxiliary tray 102. Referring to FIG. 44, the operator is instructed to remove the copy sheets in transit from auxiliary tray 102 to sorter 14. It can be envisioned that some of the duplex copies have already been made and delivered to sorter 14, while others are in transit from auxiliary tray 102, with some of the side 1 copies still remaining in tray 102. Instead of discarding the remaining side 1 copies in tray 102, it is another feature of this invention that they are further utilized to make duplex copies even though more side 1 copies may be necessary to ultimately recover for those lost in clearing the jam.

The contents of the quantity flashed counter (QTY@FLH) then is reset with the contents of copies 45 delivered counter (QTY@DLV), such counter now indicating the number of duplex copies successfully delivered to sorter 41. For purposes of illustration, assume that after clearing the jam, there are three side 1 copies remaining auxiliary tray 102, and that two completed duplex copies have reached sorter 14 successfully. Hence, the quantity flashed counter is set to the number 2 and flash lamps 37 are then activated. However, lamps 37 are deactivated as soon as the auxiliary tray 102 becomes empty as indicated by an appropriate signal from switch 110. Accordingly, only five duplex copies are successfully delivered to sorter 14. Consequently, the contents of the copies delivered (QTY@DLV) counter would now be 5. This number is stored and is utilized to twice reset the quantity flashed and delivered counters for the next two originals, i.e. the side 1 and side 2 recovery originals from which copies are needed to properly complete the copy run. It should be noted that this can be accomplished by a variety of methods depending upon the number of counters, etc. utilized. For example, in this embodiment, the same counter QTY@DLV is utilized to first count the side 1 copies delivered, and then, after delivery coincidence is used to count the side 2 or duplex copies

delivered. Consequently, when there is a fault before side 2 delivery coincidence, the necessary information for resetting the quantity flashed and copies delivered counters for the recovery originals must be temporarily stored until the proper original is presented to the machine as discussed below. In this embodiment, this is accomplished by the instructions of the flash increment routine (FLASHINC) of Table XII.

Under the instructions of the side two jam recovery routine (PROG2SJM of Table XVII), document handler 16 is recycled to bring the old side 1 original back onto platen 35 (see, e.g. GO@SIDE 1 also reproduced in Table XVII). This is accomplished by comparing the contents of the originals flashed counter (ORIG@FLH) with that of the originals delivered counter (ORIG@DLV). It should be noted that an appropriate provision can be made to deactivate flash lamps 37 until the correct original is in the platen 35. When contents of these two counters coincide, the correct original for remaking the side 1 copies is in place on platen 35. Thus, the old side 1 original is on the platen and the contents of the quantity flashed counter (QTY@FLH) is at 5, this counter having been reset to the number of side 2's delivered. Flash lamps 37 are then activated until coincidence (5 times) to provide five side 1 copies, which are placed in auxiliary tray 102. The side 2 original is then placed on platen 35, with the contents of the quantity flashed (QTY@FLH) and delivered (QTY@DLV) counters being set to 5. Lamps 37 are then flashed till coincidence to thus form five duplex on the backside of side 1 copies fed from auxiliary tray 102, with these copies being placed in sorter 14. Accordingly, the 8 duplex copies required to recover from the fault have been produced.

Referring back to FIG. 42, the remaining possibility 35 is for the fault condition to occur after side 2 flash coincidence but before side 2 delivery coincidence. In such case, the contents of the originals flashed counter (ORIG@FLH) would not be equal to the contents of the originals delivered counter (ORIG@DLV), such 40 comparison being made by the instructions included in the routine RECOV@CK reproduced in Table XVIII. Such noncoincidence is due to the fact that the side 2 original is removed from platen 35 as soon as there is flash coincidence, but before all the copies therefrom are delivered. Accordingly, the routine RECOVER 45 (Table XVIII) sets a flag indicating that the document handler 16 needs to be recycled.

Turning now to FIG. 45, the operator is instructed to remove copies not only from the paper path, but also 50 from auxiliary tray 102. For purposes of illustration, assume that after clearing the jam, there have been two successfully delivered duplex copies to sorter 14. Hence, the contents of the copies delivered counter (QTY@DLV) would be 2. Again, assume that 10 copies 55 are desired. Hence, eight duplex copies must be remade for proper completion of the copy run. With the auxiliary tray empty, the side 2 jam recovery routine (PROG2SJM) instructs the document handler 16 to recycle the originals 2 until the originals flashed counter 60 (ORIG@FLH) equals the original delivered counter (ORIG@DLV). (It will be remembered that the contents of the originals flashed counter is incremented whenever an original is removed from platen 35, even though they may not be exposed as is the case here.) In 65 such manner, the old side 1 original is automatically placed on platen 35. In the same manner as described above, the contents of the quantity flashed counter

(QTY@FLH) and quantity delivered counter are reset, for the next two originals, to the stored contents of the copies delivered counter (QTY@DLV), such counter indicating the number of duplex copies that were successfully delivered, here two in number. Flash lamps 37 are then activated to form eight copies of side 1, with such copies being placed in auxiliary tray 102. After side 1 delivery coincidence, the quantity flashed (QTY@FLH) and delivered (QTY@DLV) counters 10 are reset to 2, and the side 2 original is placed on platen 35 whereat eight copies therefrom are produced on the backsides of the side 1 copies fed from auxiliary tray 102. After side 2 flash coincidence, the contents of the counters are cleared to zero and the normal operating 15 sequence shown in FIG. 42 is repeated until the end of the copy run.

In view of the foregoing, it can now be realized that the present invention provides a method of controlling a reproduction machine to produce duplex copies automatically. Moreover, provision is made for automatically remaking lost copies due to a fault condition during the middle of a copy run. More importantly, this is accomplished by the use of a minimal number of sensors and counters, while at the same time optimizing the throughput of the machine. Therefore, while this invention has been described in connection with particular examples thereof, no limitation is intended thereby except as defined in the appended claims.

What is claimed is:

- 30 1. A method of controlling a reproduction machine to produce duplex copies from a set of original documents, said method comprising:
  - a. storing the quantity to be exposed and the quantity to be delivered to a receptacle for each original in the set for proper completion of the copy run;
  - b. exposing a side 1 original to form at least one image thereof on a photoreceptor;
  - c. forming finished copies from each image thus formed;
  - d. delivering said side 1 copies to a temporary receptacle;
  - e. counting in an exposures made counter the actual number of exposures made for each original;
  - f. counting in a copies delivered counter the number of finished copies successfully delivered to a receptacle;
  - 45 g. comparing the quantity to be exposed and the quantity to be delivered with the contents of the exposures made counter and the copies delivered counter for the side 1 copies, respectively;
  - h. presenting a side 2 original to the machine only if there is both side 1 exposure and delivery coincidence;
  - i. exposing the side 2 original to form at least one image thereof on the photoreceptor;
  - j. comparing the quantity to be exposed with the contents of the exposures made counter for the side 2 original;
  - k. feeding said side 1 copies from the temporary receptacle;
  - 50 l. forming finished copies of the side 2 original on the opposite side of the side 1 copies thereby forming duplex copies;
  - m. delivering said duplex copies to an output receptacle;
  - n. comparing the quantity to be delivered with the contents of the copies delivered counter for the side 2 original; and

wherein a fault is detected if side 1 and side 2 exposure and delivery coincidences are not met.

2. The method of claim 1 which further includes the steps of:

using a document handler device to automatically feed the originals to an exposure platen from which the originals are presented to the machine for forming images therefrom;

storing in an originals exposed counter a running count of the originals presented to the machine; 10 and

storing in an originals delivered counter a running count of the number of originals from which all the necessary copies thereof have been successfully 15 completely delivered.

3. The method of claim 2 which further includes the following steps when side 1 exposure and delivery coincidences are not met thereby automatically adjusting the reproduction process so that the selected number of 20 copies are produced;

removing copies in transit to the temporary receptacle;

resetting the exposures made counter with the contents of the copies delivered counter; and

repeating steps b-n until the selected number of copies are produced.

4. The method of claim 2 which further includes the following steps when side 2 exposures coincidence is not met thereby automatically adjusting the reproduction process so that the selected number of copies are reproduced;

removing copies in transit between the temporary receptacle and the output receptacle;

resetting the exposures made counter for the side 2 original to the contents of the copies delivered counter;

feeding the remaining side 1 copies from the temporary receptacle;

forming side 2 copies on the opposite sides of the side 1 copies until the temporary receptacle becomes empty;

delivering the duplex copies to the output receptacle;

storing the contents of the copies delivered counter whose contents indicates the number of duplex copies successfully delivered to the output receptacle;

resetting the exposures made counter and the copies delivered counter for the next two originals with the stored contents of the copies delivered counter for the duplex copies;

recycling the document handler to replace the previous original on the platen; and

repeating steps b-n until the selected number of copies are produced.

5. The method of claim 4 wherein the document handler is recycled until there is coincidence between the originals exposed and originals delivered counters 60

thereby automatically replacing the necessary side 1 original on the platen to remake the lost copies.

6. The method of claim 2 which further includes the following steps when side 2 exposure coincidence is met but side 2 delivery coincidence is not met thereby automatically adjusting the reproduction process so that the selected number of copies are produced;

removing copies from the temporary receptacle and those copies in transit to the output receptacle;

storing the contents of the copies delivered counter whose contents indicates the number of duplex copies successfully delivered to the output receptacle;

resetting the exposures made counter and copies delivered counter for the next two originals with the stored contents of the copies delivered counter for the duplex copies delivered to the output receptacle;

recycling the document handler to replace on the platen the last original from which all of the necessary copies have been successfully delivered; and repeating steps b-n until the selected number of copies are produced.

7. The method of claim 6 wherein the document handler is recycled until there is coincidence between the originals exposed and originals delivered counters thereby automatically replacing the necessary side 1 original on the platen to remake the lost copies.

8. In a reproduction machine for making duplex copies from side 1 and side 2 originals, the improvement comprising means for automatically adjusting the reproduction process in the event of a fault condition so that the selected number of copies are produced, said means including:

a first counter means for maintaining a running count of the number of exposures made of each original; a second counter means for maintaining a running count of the number of successfully delivered copies of each original;

a first flag means for signalling that copies of the side 1 original are being made;

a second flag means for signalling that copies of the side 2 original are being made;

detector means for checking the condition of the first and second flag means in the event of a fault;

means for storing the contents of the second counter when the second flag signal is present at the time of the fault;

means for twice resetting the first and second counters with the stored contents of the second counter as the next two originals are presented to the machine;

means for successively representing the previous side 1 and side 2 originals to the machine; and

means for successively making a sufficient number of copies from said side 1 and side 2 originals to bring the count of said first and second counters equal to the number of copies selected thereby remaking the copies lost due to the fault.
